(57) **CLAIM**

I claim the ornamental design for a digital camera with an animated graphical user interface, as shown and described.

DESCRIPTION

FIG. 1 is a first image of a front-side view of a digital camera with an animated graphical user interface showing my new design;

FIG. 2 is a second image thereof;

FIG. 3 is a third image thereof;

FIG. 4 is a fourth image thereof;

FIG. 5 is a fifth image thereof; and,

FIG. 6 is a sixth image thereof.

The appearance of the transitional image sequentially transitions between the images shown in FIGS. 1-6. The process or period in which one image transitions to another image forms no part of the claimed design.

The broken lines shown in the drawing illustrates the digital camera and portions of the graphical user interface that form no part of the claimed design.
